UNITED STATES PATENT OFFICE.

ROBERT T. JOHNSTON, OF CHICAGO, ILLINOIS, ASSIGNOR TO THE GOSS PRINTING PRESS COMPANY, OF CHICAGO, ILLINOIS, A CORPORATION OF ILLINOIS.

PRINTING-PRESS.

1,112,141.

Specification of Letters Patent. Patented Sept. 29, 1914.

Application filed November 17, 1913. Serial No. 801,467.

To all whom it may concern:

Be it known that I, ROBERT T. JOHNSTON, a citizen of the United States, residing at Chicago, in the county of Cook and State 5 of Illinois, have invented certain new and useful Improvements in Printing-Presses, of which the following is a specification, reference being had to the accompanying drawings.

10 My invention relates to printing presses, and has particularly to do with flat bed web presses of the reciprocating cylinder and stationary bed type arranged to print on each stroke of the impression cylinder or 15 cylinders. In presses of this type, for example, a two cylinder press, as each impression cylinder during a part of each stroke presses the web down upon a stationary form, it is, of course, necessary that while 20 printing is being done the web remains stationary, and as the feeding in rollers feed web continuously to the press and the feeding out rollers draw the web out of the press and feed it to the folder continuously, 25 suitable web compensating mechanism is provided to maintain the proper tension on the web between the feeding in rollers and the first impression cylinder, and between the second impression cylinder and the feed- 30 ing out rollers to prevent breakage at those points. Web compensating mechanism for this purpose, in itself, is old and in common use. In presses of this character it is also necessary to provide inking rollers at 35 each side of the impression cylinder or cylinders so as to properly ink the form or forms after each imprint is made, and in order that the inking rollers may pass completely across the surface of the form, the 40 stroke of the cylinder is enough greater than the length of the form so that the following inking roller moves completely across the form on each stroke of the cylinder. In 45 presses of this type as heretofore constructed, as soon as an imprint is made and before the cylinder reaches the end of its stroke, the web again begins to travel, being pulled through the press by the combined effort of the feeding out rollers and the 50 cylinder compensating mechanism, so that it is drawn around the impression cylinder, slipping over the surface thereof. The friction existing between the web and the cylinder, therefore, increases the tension 55 upon the web to an objectionable extent,

which frequently results in breakage of the web, with ensuing trouble and delay.

The object of my present invention is to avoid this objectionable slipping of the web over the impression cylinder or cylinders, 60 and to that end to provide a construction by which the surface of the impression cylinder or cylinders will always move with the web when the web is moving, regardless of the direction in which the cylinder as a 65 whole is traveling.

I accomplish this object as illustrated in the drawings and as hereinafter described.

What I regard as new is set forth in the 70 claims.

In the accompanying drawings, in which I have illustrated my improvements as applied to one of the cylinders of one-half of a double width flat bed perfecting press,— Figure 1 is a side elevation of my improved 75 press, some parts being in longitudinal section; Fig. 2 is a partial plan view; Fig. 3 is a detail showing my improved cylinder compensating mechanism; Fig. 4 is a detail illustrating the mechanism for driving said 80 cylinder compensating mechanism.

Referring to the drawings,—6 indicates the frame of the press, which may be of any suitable form and construction.

7—8 indicate two stationary flat beds 85 upon which the forms are placed, one of said beds being above the other and separated therefrom far enough so that the parts operating on the lower bed may be arranged between them. 90

9—10 indicate inking fountains at opposite ends of the lower bed, said fountains having the usual fountain rollers 11—12, respectively.

13—14 indicate similar inking fountains 95 associated with the upper bed 8, and having rollers 15—16.

17 indicates a bracket, one of which is provided at each side of the press, which brackets form supports for lower and upper 100 impression cylinders 18—19, which extend across the press above the beds 7—8, respectively. The brackets 17 are preferably cross-shaped, their horizontal portions having the usual guide blocks which run in ways 105 provided in the frame of the press, so that the cylinders 18—19 may be moved back and forth over their respective beds. The cylinders 18—19 are reciprocated longitudinally of the press by means of a pitman 22 110.

on each side of the machine, each of which is connected by a wrist pin 23, with a gear 24, mounted on a drive shaft 25, as shown in Fig. 1. The gear 24 rotates in the direction indicated by the arrow in said figure. 5 26 indicates the web roll, and 27 the web. The web 27 passes from the web roll over suitable guide rolls 28—29, feed roll 30, and guide roll 31, any desired number of which 10 guide rolls may be used and which are arranged in such locations as to properly conduct the web. From the guide rolls the web is looped around a web compensating roll 32, carried by arms 33, of brackets 34, 15 one of which is provided at each side of the press. These brackets are movable longitudinally of the press toward and from the beds 7—8 by suitable cam mechanism which will be hereinafter described, said brackets 20 having longitudinally extending blocks 35—36, which move in suitable guide ways provided on the frame of the press. After passing around the web compensating roll 32, the web passes around a guide roll 37, 25 and thence over a guide roll 38, carried by the brackets 17; thence down around the impression cylinder 18; thence up over another guide roll 39, carried by the brackets 17; thence around guide rolls 40—41, 30 carried by the frame of the press; thence around a guide roll 42, carried by the brackets 17 adjacent to the upper impression cylinder 19; thence down around the latter impression cylinder and up to another guide roll 35 43, carried by the brackets 17, after which it is looped around a web compensating roll 44, carried by upwardly-projecting arms 45 of the brackets 34; thence around guide rolls 46—47, carried by the frame of the press; 40 and thence to the feeding out roller and cutting and folding mechanism. It will be observed that by looping the web around the web compensating rolls 32 and 44, when the brackets 34 which carry said rolls move to 45 the left, which occurs during the printing operation, the length of the pathway of that portion of the web between the web roll 26 and the lower impression cylinder will be lengthened so as to take up any slack that 50 may exist in that portion of the web. At the same time the length of the pathway of that portion of the web between the upper impression cylinder and the folding devices will be shortened, thereby giving up web to the folding devices so that 55 the portions of the web being printed may remain stationary. This operation is very much the same as in prior presses of this character, although the specific mechanism 60 is different.

The brackets 34 are reciprocated by means of a lever 48, pivoted at 49, upon a bracket 50, and having a roller 51 which moves in a cam groove 52, provided in a disk 53, which 65 is mounted upon the shaft 25. The lever 48

is connected with one of the brackets 34 by a connecting rod 54, as shown in Fig. 1. The cam is so shaped as to properly time the movement of the brackets 34 and regulate the length of their stroke, as hereinafter set 70 forth.

The operation of the machine as thus far described will be readily understood by those familiar with the art. The web passing into the press in the manner described 75 will be printed simultaneously on both surfaces, the two impression cylinders moving in the same direction. While the imprint is being made, those portions of the web on which the printing is being done are stationary so far as longitudinal movement is concerned; consequently it is necessary that at such times that portion of the web between the feeding in rollers and the lower impression cylinder be taken up sufficiently 80 to compensate for the normal travel of that portion of the web during the printing operation. This is accomplished by the movement to the left of the web compensating roll 32, which increases the length of the 85 pathway of that portion of the web sufficiently to make the necessary compensation. In like manner, as the web continues to move through the feeding out rollers and into the folding mechanism while the printing is being done, it is necessary that the folding mechanism be supplied with web notwithstanding the stoppage of the portion being printed, and this is accomplished by the movement to the left of the web compensating roll 44, which reduces the length of the pathway of that portion of the web sufficiently to provide the necessary compensation. After each printing operation the 90 printed portions must be advanced quickly 95 enough to compensate for their stoppage, and this is done by movement of the web compensating rolls 32 and 44 in the opposite site direction.

I come now to the subject-matter with 100 which this application has more particularly to do, to-wit, the mechanism for rotating the impression cylinder or cylinders so as to cause their surfaces to move with the web during the intervals between successive imprints, and to roll naturally over the web when printing. In this connection it should be explained that while in the drawings I have shown mechanism for this purpose applied only to the upper, or second, impression cylinder, it may be applied to the first impression cylinder as well, and may be employed in presses having any desired number of impression cylinders, from one up.

Such improved mechanism comprises the 105 following instrumentalities: *a.* Cylinder rotating means adapted normally to rotate the cylinder if it is not traveling at a surface speed equal to the normal rate of travel of the web through the press, and in the 110

same direction; and *b*. Cylinder compensating mechanism coöperating with the web compensating mechanism, for varying the rotative effect upon the cylinder of said cylinder rotating means in such manner as to compensate for the travel of the cylinder back and forth over the web, and so maintain constant the actual surface movement of the cylinder with reference to the web 10 at all stages of its operation.

In the embodiment of my invention illustrated in the drawings, the cylinder rotating means (*a*) above referred to comprises a link belt or chain which is constantly driven in the same direction as the web, and at a speed uniform with the normal rate of travel of the web through the press, by which I mean the rate of speed at which the web is forwarded by the feeding rollers. 15 The cylinder compensating mechanism (*b*) above mentioned comprises a shiftable carrier for said chain associated with the web compensating mechanism and coöperating therewith to shift said chain with reference to the cylinder so as to vary its rotative effect thereupon and compensate for the reciprocation of the cylinder, the changes in the direction of rotation of the cylinder incident to its reciprocation, and the necessary variation in the speed of the web due 20 to its stoppage during printing and its speeding up thereafter.

Referring now to the drawings for a more particular description of the illustrated embodiment of the mechanism just referred to,—56 indicates a sprocket wheel, secured at one end of the upper impression cylinder 19, preferably upon the shaft or axis of said cylinder. Said sprocket wheel is adapted to 25 engage a link belt or chain 57, which is looped around or mounted upon idle pulleys or wheels 58—59, which are mounted on studs 58a—59a supported and arranged at opposite ends of the bed 8 and are connected together by a rod 60, or other suitable connection, so that said pulleys are held a fixed distance apart and may be moved longitudinally of the press in unison, thus constituting a shiftable carrier for the belt 57. 30 The manner in which these pulleys are mounted is best shown in Figs. 1 and 2. The rod 60 is connected at one end with the arm 35 of one of the brackets 34, so that when said bracket moves longitudinally of the press it moves the pulleys 58—59 and the link belt 57 mounted on them correspondingly. The belt 57 is driven constantly at the normal speed of the web, by a sprocket wheel 61 which meshes with the 35 lower portion of said belt and is arranged substantially in line with the longitudinal center of the upper bed 8, as shown in Fig. 1. Said sprocket wheel is mounted on a shaft 62, which carries a beveled gear 63, the latter meshing with a beveled gear 64,

mounted on a shaft 65, which is driven from the drive shaft 25 by means of gears 66—67, as best shown in Fig. 4. It will thus be seen that the belt 57 is continuously and uniformly driven while the press is in operation, moving in the direction indicated by the arrows in Fig. 3. For convenience, this movement of the belt will be termed its "progressive" movement. It will also be apparent that the upper portion of said belt may be moved longitudinally in either direction without regard to the motion imparted to it by the driving sprocket wheel 61, by moving its carrier longitudinally of the press, which movement is effected by the 40 cam mechanism which operates the web compensating devices, and is therefore uniform with the movement of such compensating devices. This may conveniently be termed the "shifting" movement of the belt. This shifting movement of the belt is analogous to the action of the web due to the movement of its compensating devices, since the belt is looped around its pulleys in much the same way that the web 45 is looped around the web compensating rolls 44 and 32, and it directly varies its driving effect upon the impression cylinder in such manner as to cause said cylinder to roll over the web in the proper direction while 50 printing, and at other times, while the web is in motion, causes said cylinder to rotate with the web and at a surface speed which is always the same as the speed of the web, 55 as will presently be described.

The inking of the forms is accomplished by inking rollers 68—69, arranged at opposite sides of each of the impression cylinders, and supported in any suitable way. The inking rollers 68—69 are of composition and are adapted to contact respectively with the rollers 15—16 when the impression cylinders are reciprocated, so as to take up ink from them and apply it to the type. It will be apparent that as the 60 impression cylinders move across the forms in printing, the inking roller which is back of or follows the impression cylinder must pass completely across the form in order to ink it properly for the next imprint. 65 This movement carries the impression cylinder beyond the form and releases that portion of the web which has just been printed so that it may again travel; the same operation taking place at the end of 70 each stroke of the cylinder.

Following the movement of the press from the position shown in Fig. 1, the cylinders continue to move across the form to the left. The portion of the web around the cylinders 75 is at rest and the web compensating roller 32, takes up the web fed to it by the feeding-in roller, and the web compensating roller 44 gives off the web that is being fed out by the feeding-out roller. As the form and 80

4

web are stationary, the upper portion of the chain also must be stationary, in order that the cylinder will have a perfect rolling action without slippage as it moves across the 5 form. The progressive movement of the chain, therefore, must be nullified and this is done by shifting the chain bodily with its carrier to the left at one-half the speed of its progressive movement. By following the 10 movement of the chain at this moment, it will be noted that the driven side is traveling in the direction of the rotation of the driver and at one-half the progressive speed of the driver. The remaining half of the 15 progressive speed, therefore, drives the upper portion of the chain in the opposite direction, which, of course, nullifies the shifting movement of that portion of the chain to the left. 20 It should be pointed out here, that the development of the cam is such as to give a uniform movement to the carrier and compensators to the left, so as to compensate for the progressive movement of the chain 25 and the normal movement of the web, while in the opposite direction the development of the cam is preferably harmonious, so as to have the easiest possible action on the web and cylinder turning mechanism. This condition continues until the cylinders reach 30 the left-hand edge of the form. At this point the chain carrier and web compensators reach the extreme movement to the left and as the chain and web compensators 35 come to rest at the moment of reversal, then the full progressive movement of the chain becomes effective and the web moves around the cylinders and through the machine at the normal speed of the feeding rollers. It 40 has been explained that the progressive movement of the chain and the normal speed of the feeding rollers are equal and the surface speed of the cylinders at this moment, must therefore, be in unison with the web. 45 Continuing the movement of the cylinders from the left hand edge of the form to the extreme left hand position and the return to the form, the web compensators and chain carrier in the meantime have moved from 50 the extreme left hand position to the right hand position. The action of the web compensators at this time is such as to draw through the machine the web that was held stationary during the printing portion of 55 the stroke, which in addition to the normal feed of the web through the machine during the time the cylinders are off the form, advances the web the full length of the sheet being printed. At the same time the shifting 60 action of the chain carrier is such as to move the driving side of the chain in the direction opposite to the revolution of its driver, increasing the speed in this way, as well as increasing the bodily forward shift 65 ing of the upper portion of the chain, the

total of which causes the upper portion of the chain which drives the cylinders to move at the speed of the web and drive the surface of the cylinder in unison with the web. When the cylinders reach the form on the 70 return movement the web compensators and chain carrier again move to the left, stopping the upper portion of the chain which drives the cylinder, and holding the portion of the web around the cylinders at rest 75 while it is being printed.

From the foregoing description it will be observed that the cylinder at all times when the web is in motion, rotates with the web in such manner that its surface speed exactly corresponds with the speed of the web, and that when printing the cylinder rolls in the proper direction over the form so as to make the imprint properly. It is impossible for the speed of the cylinder to vary 80 from that of the web because the cylinder compensating mechanism which regulates the direction of rotation and speed of the cylinder is coupled up with the web compensating mechanism and is controlled by the 85 same cam.

Se far as I am aware, I am the first in the art to provide a flat bed web press with means for rotating the cylinder or cylinders with the web at all times while the 90 web is in motion. I also believe myself to be the first in the art to provide means for rotating the cylinder, in connection with cylinder compensating mechanism coacting therewith to regulate the direction and speed 95 of the cylinder for the purpose specified; also to provide such cylinder compensating mechanism in association with web compensating mechanism. My invention is therefore generic in character and the claims 100 hereinafter made are to be construed according.

That which I claim as my invention, and desire to secure by Letters Patent, is,—

1. A printing press of the type described, 110 comprising means for advancing the web, an impression cylinder, a stationary form, and reciprocating means for rotating said cylinder with the web while the web is advancing.

2. A printing press of the type described, comprising means for advancing the web, an impression cylinder, a stationary form, reciprocating means for rotating said cylinder with the web while the web is advancing, and means for rolling the cylinder over 120 the web during printing.

3. A printing press of the type described, comprising means for advancing the web, an impression cylinder, a stationary form, 125 traveling means for rotating said cylinder with the web while the web is advancing, and means for reciprocating said traveling means.

4. A printing press of the type described, 130

- comprising means for advancing the web, an impression cylinder, a stationary form, means for reciprocating the cylinder, a traveling member operatively connected with said cylinder to rotate the same, means for driving said traveling member at a normal speed, and means coöperating with said cylinder reciprocating means for varying the rotative effect of said traveling member upon the cylinder to cause the cylinder to roll over the web while the same is being printed. 5. A printing press of the type described, comprising means for advancing the web, a cylinder, a stationary form, means for reciprocating the cylinder, means adapted to be operated to rotate the cylinder with the web while the web is advancing, and means coöperating with said cylinder reciprocating means for varying the operation of said cylinder-rotating means to cause the cylinder to roll over the web during printing. 6. A printing press of the type described, comprising means for advancing the web, a stationary form, a cylinder, web compensating mechanism, and movable means for rotating the cylinder with the web while the web is advancing. 7. A printing press of the type described, comprising means for advancing the web, a stationary form, a cylinder, web compensating mechanism, movable means adapted to be operated to rotate the cylinder with the web while the web is advancing, and means for rolling the cylinder over the web during printing. 8. A printing press of the type described having a stationary form, means for advancing the web, a cylinder, means for reciprocating the cylinder over the form, web compensating mechanism, and means coacting with said compensating mechanism for rotating the cylinder with the web while the web is advancing. 9. A printing press of the type described, comprising means for advancing the web, a cylinder, a stationary form, web compensating mechanism, and means coacting with the web compensating mechanism for rotating the cylinder with the web while the web is advancing. 10. A printing press of the type described, comprising means for advancing the web, a cylinder, a stationary form, web compensating mechanism, and means associated with said compensating mechanism and acting to rotate the cylinder at a surface speed equal to the rate of travel of the web while the web is advancing. 11. A printing press of the type described, comprising means for advancing the web, a cylinder, web compensating mechanism, means associated with said compensating mechanism and acting to rotate the cylinder at a surface speed equal to the rate of travel of the web while the web is advancing, and means for reciprocating said cylinder. 12. A printing press of the type described, comprising means for advancing the web through the press at a normal speed, a cylinder, driving means adapted to rotate said cylinder in unison with the normal speed of the web through the press, and cylinder compensating mechanism associated with said driving means for varying the rotative effect thereof on the cylinder to maintain the surface speed of said cylinder uniform with the speed of the web when the web is advancing. 13. A printing press of the type described, comprising means for advancing the web through the press at a normal speed, a cylinder, driving means adapted to rotate said cylinder in unison with the normal speed of the web through the press, cylinder compensating mechanism associated with said driving means for varying the rotative effect thereof on the cylinder to maintain the surface speed of said cylinder uniform with the speed of the web when the web is advancing, and web compensating mechanism. 14. A printing press of the type described, comprising means for advancing the web through the press at a normal speed, a cylinder, driving means adapted to rotate said cylinder in unison with the normal speed of the web, and cylinder compensating mechanism associated with said driving means and acting to shift the same to vary its rotative effect on the cylinder and maintain the surface speed of said cylinder uniform with the speed of the web while the web is advancing. 15. A printing press of the type described, comprising means for advancing the web through the press at a normal speed, a cylinder, driving means adapted to rotate said cylinder in unison with the normal speed of the web, cylinder compensating mechanism associated with said driving means and acting to shift the same to vary its rotative effect on the cylinder and maintain the surface speed of said cylinder uniform with the speed of the web while the web is advancing. 16. A printing press of the type described, comprising means for advancing the web through the press at a normal speed, a reciprocating cylinder, driving means adapted to rotate said cylinder in unison with the normal speed of the web, cylinder compensating mechanism associated with said driving means and acting to shift the same to vary its rotative effect on the cylinder and maintain the surface speed of said cylinder uniform with the speed of the web while the web is advancing.

speed of said cylinder uniform with the speed of the web while the web is advancing, and web compensating mechanism co-operating with said cylinder compensating 5 mechanism:

17. A printing press of the type described, comprising means for advancing the web through the press at a normal speed, a reciprocating cylinder, a shiftable carrier, 10 driving means looped upon said carrier for rotating said reciprocating cylinder, said driving means having a constant progressive movement equal to the normal speed of the web through the press, and means for shifting 15 said carrier to vary the rotative effect of said driving means upon the cylinder so as to maintain the speed of the cylinder uniform with the web when the web is advancing.
18. A printing press of the type described, comprising means for advancing the web through the press at a normal speed, a reciprocating cylinder, a shiftable carrier, 20 driving means looped upon said carrier for rotating said reciprocating cylinder, said driving means having a constant progressive movement equal to the normal speed of the web through the press, and means for shifting 25 said carrier to vary the rotative effect of said driving means upon the cylinder so as to maintain the speed of the cylinder uniform with the web when the web is advancing and to cause the cylinder to roll over the web during printing.

19. A printing press of the type described, comprising means for advancing the web through the press at a normal speed, a reciprocating cylinder, web compensating mechanism, a shiftable carrier, driving 40 means looped upon said carrier and having a constant progressive movement equal to the normal speed of the web through the press, and means co-operating with said web compensating mechanism for shifting said 45 carrier to vary the rotative effect of said driving means upon the cylinder so as to maintain the speed of the cylinder uniform with the web when the web is advancing.

20. In a press of the type described, the 50 combination with a reciprocating impression cylinder and web compensating mechanism, of an endless belt associated with said cylinder for rotating the same, a reciprocating carrier for said belt, means associated with 55 said web compensating mechanism for reciprocating said carrier, and means for driving said belt.

21. In a press of the type described, the 60 combination with a reciprocating impression cylinder and web compensating mechanism, of an endless belt associated with said cylinder for rotating the same, a reciprocating

carrier for said belt, means associated with said web compensating mechanism for reciprocating said carrier, and means independent of the reciprocation of said carrier for driving said belt constantly in the same direction. 65

22. In a press of the type described, the combination with means for advancing the web through the press at a normal speed, a reciprocating impression cylinder and web compensating mechanism, of an endless belt associated with said cylinder for rotating the same, a reciprocating carrier for said 70 belt, means associated with said web compensating mechanism for reciprocating said carrier, and means independent of the reciprocation of said carrier for driving said belt constantly in the same direction at the 75 same speed as the normal speed of the web through the press.

23. In a press of the type described, the combination with a reciprocating impression cylinder and web compensating mechanism, 80 of an endless belt associated with said cylinder for rotating the same, a reciprocating carrier for said belt, means connecting said carrier with said web compensating mechanism, and means for driving said belt, said 85 carrier being movable independently of said driving means.

24. A printing press of the type described, comprising means for advancing the web, an impression cylinder, a stationary form, 90 means for reciprocating the cylinder, a traveling member operatively connected with said cylinder to rotate the same, means for driving said traveling member at a normal speed, and means co-operating with said cylinder reciprocating means for varying the 95 rotative effect of said traveling member upon the cylinder to cause the cylinder to roll over the web while the same is being printed and to rotate with the web when the 100 web is in motion.

25. A printing press of the type described, comprising means for advancing the web, an impression cylinder, a stationary form, means for reciprocating the cylinder, a traveling member operatively connected with said cylinder to rotate the same, means co-operating with said cylinder reciprocating means for driving said traveling member at a normal speed, and means for reciprocating 110 said traveling member to vary the rotative effect thereof upon the cylinder so as to cause the cylinder to roll over the web while the same is being printed and to rotate with the web when the web is in motion.
